UNITED STATES PATENT OFFICE

JOHN HILL, OF WEST MERIDEN, CONNECTICUT, ASSIGNOR TO THE MERIDEN SILVER-PLATE COMPANY, OF SAME PLACE.

DESIGN FOR A BUTTER-DISH.

Specification forming part of Design No. 5,839, dated May 7, 1872.

To all whom it may concern:

Be it known that I, JOHN HILL, of West Meriden, in the county of New Haven and State of Connecticut, have invented a new Design for Butter-Dish; and I do hereby declare the following, when taken in connection with the accompanying drawing and the letters of reference marked thereon, to be a full, clear, and exact description of the same, and which said drawing constitutes part of this specification and represents a side view.

This invention relates to a design for a covered butter-dish, intended to be made from metal; and the design consists in the peculiar configuration of the dish, as shown in the accompanying illustration, and as hereinafter described.

B is the body or bowl of the dish, supported upon legs A, and rises in an expanding curve to a point, a, then in a contracting curve to the neck d, into which the cover C sets. The cover rises in conical form, and terminates in a molded cap, D, surmounted with an ornament which serves as a handle, here represented as a butterfly. To the dish proper ears E are attached, and to these a bail, F, by means of which to raise the dish.

I claim as my invention—

The design for butter-dish as shown and described, and with or without the bail F.

JOHN HILL.
